UNITED STATES PATENT OFFICE.

ARTHUR A. BRONSHVAG, OF NEW YORK, N. Y.

PICTURE MOUNTING.

1,403,537.

Specification of Letters Patent. Patented Jan. 17, 1922.

Application filed May 31, 1921. Serial No. 473,961.

To all whom it may concern:

Be it known that I, ARTHUR A. BRONSHVAG, a citizen of the United States, residing at New York city, in the county of the Bronx and State of New York, have invented new and useful Improvements in Picture Mountings, of which the following is a specification.

My invention embodies certain novel features in picture mounting with the object to provide in an ordinary mounted picture, adjustable releasable clasps that will permit the use of metal frames stamped whole from a sheet metal plate, making for great economy in manufacture—as will be subsequently explained—and which clasps will insure sufficient pressure between the mounting and the frame for the purpose of securely and releasably holding the mounting in place.

In the accompanying drawing: Figure 1 is a plan view of the frame with only part of the mounting and the clasps shown; Fig. 2 is an enlarged section on line 2—2 in Fig. 1; Fig. 3 is a view on line 3—3 in Fig. 2; Figs. 4 and 5 are modifications of Fig. 2; Fig. 6 is a modification of Fig. 2; Fig. 7 is a plan view taken on line 7—7 in Fig. 6.

In order to attain the objects set forth, I provide for a frame 1, stamped out whole of one piece of sheet metal with enough dish and ornaments to suit appearance, stiffness of the frame and the contemplated selling price of same. Wire members 2 of U-shape are inserted at intervals through perforations in the frame in a manner shown in Figs. 1, 2 and 3. The clasps 3, having perforations to suit the U members, are then placed in a manner shown in Figs. 2 and 3 supported on the frame 1 and the mounting 5. The free ends of the U members are then bent as shown in Fig. 3, thus putting any desired pressure on the clasps which transmit the pressure to the mounting and against the frame thus serving to hold the said mounting in place.

These U members can be used to hold insertions 4, Figs. 6 and 7, of any design placed on the face of the frame and having perforations to suit the U members, and which insertions will make a beautiful contrast with the frame when painted a different color from the frame.

Another use for these U members is to serve the purpose of stops for the mounting

against moving in a direction in the prolongation of its plane when it is mounted.

Two of these U members in a line parallel to the bottom of the mounted picture can further be used as attachments to which a wire or string can be tied for the purpose of hanging said picture from same U members.

A modification, whereby a bolt 2^a is substituted for the U member, is shown in Fig. 4. The pressure on the clasp in this case, is increased or decreased by turning the nut down or up respectively.

Fig. 5 shows a rivet 2^b used where a bolt was used in Fig. 4. The tension member 70 is thereby made to be an integral part of the clasp, the two combined resembling a W in shape—as disclosed by Fig. 2. The central tip is made integral with the frame, one end tip is resting on frame and the other 75 end tip is resting on the mounting that is being held against the frame by the said clasps. By pressing one or both tips of the W in or out—which is equivalent to shortening or lengthening the tension members previously described—adjustable pressure is 80 brought to bear on the mounting and against the frame.

To release the mounting in any one of the three cases cited, the clasps are turned 85 about their central parts till the tips resting on the mounting are off it. The two tips of each clasp lie then in a line parallel, or nearly so, to the edge of the mounting.

Thus I provide a sure, simple and economic way of holding a mounting against a frame, and which can be adopted to serve for a metallic frame; serving the ends of economy. For, for the cost of the metal taken up by the frame proper (the piece 90 cut out can be used for a smaller frame and the process continued reducing waste to a minimum), plus the insignificant cost of stamping the same, plus the cost of the clasps and tension members, I produce a 100 finished frame having any beautiful design stamped upon it. Comparing this with the present cost of picture frame moulding and the cost of putting same together, the economy of my suggestion is apparent.

While these clasps and tension members are primarily designed to be used with metal frames, they can be used with wooden frames also; particularly with common mouldings, in which case these clasps and tension mem- 110

bers serve the identical purpose as for metal frames.

Changes in the outline and proportion of the clasp and tension members, may be resorted to, without sacrificing any of the advantages of my invention as defined in the appended claims.

Having thus described my invention, I claim:

10. 1. In combination, a frame having an inner ledge, a picture bearing against said ledge, perforations in the ledge, clasps to hold the picture against the ledge, each clasp comprising a sheet metal U-shaped member pressing the picture mount against the ledge, and a staple passing through the perforations in the ledge and the yoke of the sheet metal member and clasping said member and the picture against the frame.
15. 2. In combination, a picture frame having an inner ledge, perforations in said ledge, ornamental members covering said perforations, a picture bearing against the underside of the ledge, means holding the pic-

ture against the ledge, and means passing through the ornamental members and the perforations and holding said means against the picture.

3. In combination, a clasp for holding a picture in the frame and comprising a sheet metal U-shaped member one arm of which bears against the underside of the picture near its edge and its other arm bearing against the frame, a wire staple passing through the frame and the yoke of the U-shaped member and having its ends clenched against said yoke, to clamp the edge of the picture between the frame and the one arm of the U-shaped member, the side of the staple abutting the outer edge of the picture and preventing its edgewise movement.

Subscribed to in the presence of two witnesses, this 28th day of May, 1921.

ARTHUR A. BRONSHVAG.
